UNITED STATES PATENT OFFICE.

FRED M. JOERNNDT AND WILBUR A. JOERNNDT, OF CHICAGO, ILLINOIS; SAID WILBUR A. JOERNNDT ASSIGNOR TO SAID FRED M. JOERNNDT.

PRINTER'S MAGAZINE RACK.

Application filed March 1, 1928. Serial No. 258,345.

This invention relates to improvements in printer's magazine racks, such as are used in holding linotype machine matrices.

The principal object of the invention is 5 to provide an improved rack of simple and economical construction which will hold the magazines in compact relation but which permits the loading and unloading of the magazines with minimum effort and without 10 interference or obstruction with any portion of the supporting apparatus.

Other objects relate to various features of construction and arrangement of parts which will become apparent from a consideration 15 of the following specification and accompanying drawings wherein:

Figure 1 is a perspective view of a rack having a plurality of magazine supporting carriers, 20 Fig. 2 is a detached view of a magazine carrier showing a magazine in position therein,

Fig. 3 is a vertical section through the rack illustrating the construction common to each 25 carrier,

Fig. 4 is an enlarged sectional detail plan view of the rear end of a carrier and related portion, taken on line 4—4 of Fig. 3,

Fig. 5 is an enlarged detail plan view of 30 the rear portion of the carrier, the upper track being broken away for the purpose of clearness,

Fig. 6 is a broken vertical sectional view taken on line 6—6 of Fig. 3.

The apparatus comprises a suitable supporting structure having front corner posts 10, 10 which may be of angle iron, and similar rear corner members 11, 11. The ends and rear portions may be suitably braced to 40 provide a rigid structure and, except for the front, is preferably provided with a sheet metal casing 12 to exclude dust and other foreign matter from the magazines and to protect the same against fire.

45 connecting the rear posts 11 adjacent the upper ends thereof is a horizontal cross plate 13 which is riveted or otherwise secured to the posts. Joining the front posts 10 are two spaced plates 14, 15 similarly secured. These front and rear plates support 50 track members 16, 17 respectively, there being as many pairs of tracks as there are magazines to be supported by the rack.

The tracks 16, 17 are preferably formed of

metal tubes which may be bolted as at 18, 55 19 to the plates 14, 15 respectively and held by nuts to the plate 13, or they may be otherwise secured in position.

The magazine carrier comprises a trolley wheel 20 which is journaled between the 60 arms 21 of the rear end of the carrier bar 22. The arms 21 may be riveted to the bar 22 as shown in Figure 5 or other suitable construction may be employed. The trolley 20 is positioned between the upper and lower 65 tracks 16 and 17 and is adapted to bear against one or the other during the movement of the carrier in use. The forward end of the carrier bar 22 extends through the space between the plates 14, 15, the lower 70 plate being provided with a notch 23 for guiding the bar in the plane of the vertically alined track members. (See Fig. 6.)

Extending transversely of the rack, adjacent the front thereof, is a rod 24 which 75 may be secured at its ends to the front corner posts 10. Spaced along the rod 24, in alinement with the slots 23, are rollers 25 which support the forward ends of the bars 22 and upon which the bars roll when the 80 carriers are operated. Other friction reducing means may of course be used if desired.

The forward end of the carrier bar 22 extends beyond the front of the rack, and has 85 a magazine hanger 26 secured thereto which is curved or inclined to the rear as shown. Intermediate the ends of the hanger a portion is turned upwardly to form a hook 27 as shown in Figure 3. A similar hanger 28 90 is secured to the rear end of the bar 22, said hanger however being inclined toward the front of the rack, and is provided with a hook 29 similar to hook 27 and as the same height as the latter. The hangers 26 and 95 28, as will be seen in Figure 3, each have a portion 26^a and 28^a respectively, which extend some distance below the hooks.

A magazine of the standard or conventional form is of the general shape shown 100 in the drawings, and as standard practice has a cross bar 31 by means of which it is supported in racks when not in use. The ends of the bar project slightly beyond the edges of the magazine and are adapted to 105 seat in the hooks 27, 29 as shown. As illustrated in Figure 3, a substantial portion of the hangers contact with the magazine both

above and below the supporting hooks 27, 29, and thus prevent the magazines from swinging or tilting on the cross bars 31.

When it is desired to remove a magazine 5 from a rack, the carrier is pulled forwardly, a suitable handle (not shown) being provided on the end of the carrier for this purpose, if desired. The carrier will move easily as the trolley travels on the lower 10 track 17 while the forward end of the bar rides on the roller 25. When the carrier reaches the outer position, it will tilt slightly about the roller 25 as a pivot, which movement will carry the trolley into contact with 15 the upper track member 16. This tilting movement is very slight as the tracks are spaced to prevent any jolting of the carrier and magazine as will be seen. (See Fig. 4.) This construction provides a freely running 20 carriage which does not bind on its supporting members as the leverage upon the bar approaches the maximum due to the carrier being drawn to its outer-most position indicated by dotted lines in Figure 3. 25 As illustrated in Fig. 3, the inclination of the rear hanger 28 is such that the hook 29 is clear of the forward portion of the rack when the carrier is in the dotted line position just mentioned. It will be obvious that 30 a magazine can be loaded on the carrier, or removed therefrom without the least obstruction from any part of the apparatus and that when the carrier is so loaded it can be moved easily to its inner position. When 35 the carriers are in their inner positions the magazines are entirely within the rack structure.

One or more shelves 32 may be secured to the corner legs 10, 11 beneath the mechanism described above as shown in Figure 1.

Although we have shown and described certain features of our improvements for the purpose of illustration, it will be apparent that various changes may be made therein without departing from the spirit of the invention as defined in the appended claims.

What we claim is:

1. A printer's magazine rack comprising a supporting frame, a horizontally disposed track carried thereby extending from front to rear thereof, and a carrier movable along said track, said carrier being provided with a pair of hangers having magazine supporting members, said hangers being inclined downwardly and toward the center of the frame whereby said supporting members are clear of the frame when the carrier is in the forward position and are within the rack when the carrier is in the rear position.

60 2. A printer's magazine rack comprising a supporting frame, a horizontally disposed track supported by the frame, a carrier movable along the track, said carrier having a front hanger and a rear hanger secured thereto, said hangers being provided with

magazine supporting members, said carrier being movable to a position wherein both said magazine supporting members are clear of the frame whereby a magazine can be positioned on or removed from said members without obstruction by the frame and is movable inwardly to a position wherein the magazine is entirely within the rack. 70

3. A printer's magazine rack comprising a supporting frame having front and rear cross plates, a pair of track members extending horizontally between said plates, said tracks being disposed in spaced relation and in the same vertical plane, and a horizontally movable magazine carrier comprising 75 a bar disposed substantially parallel to said track members and being provided with a trolley supported and guided by said track members during the movement of the carrier. 80

4. A printer's magazine rack comprising a frame, a pair of horizontally disposed vertically aligned track members supported by said frame, and a magazine carrier movable along the track members, said carrier comprising a bar, a trolley secured thereto between said track members, and a pair of hangers having means for engaging and supporting a magazine in vertical position below said track members. 90

5. A printer's magazine rack comprising a frame, a pair of horizontally disposed vertically aligned track members supported by said frame, and a magazine carrier movable along said track members, said carrier comprising a bar, a trolley secured thereto between said track members, and a pair of hangers having means for engaging and supporting a magazine in vertical position below said track members, said hangers having 100 extensions below said supporting means adapted to cooperate with upper portions of the hangers to prevent tilting of the magazine when in position on said means. 105

6. Apparatus of the class described comprising a supporting frame, a pair of spaced front plates extending transversely of the frame, a rear plate parallel to said front plates, a pair of horizontally disposed vertically aligned track members one secured to each of said front plates and both secured to the rear plate, a magazine carrier member comprising a bar disposed between said track members and being provided with a supporting trolley adjacent its rear end, said trolley being supported and guided by said track members, the forward portion of said bar extending between said front plates, and a pair of hangers one secured to said bar forwardly of said front plates and the other being secured to the bar forwardly of the trolley, said hangers being adapted to support a magazine in vertical position and to prevent the same from swinging from such position. 110 115 120 125 130

7. A printer's magazine rack comprising a supporting frame, a horizontally disposed track member extending from front to rear supported by the frame, a carrier comprising 5 a bar having a trolley secured to the rear end thereof, said trolley being adapted to travel on said track, a roller adjacent the forward end of the track for supporting said bar, said bar at the forward end extending beyond the front of the frame, a hanger secured to the forward end of the bar and extending downwardly and inwardly to a position within the frame, a second hanger 10 secured to the rear portion of said bar and being inclined downwardly and forwardly, said hangers having magazine supporting hooks open at the top for permitting a magazine to be freely positioned thereon or re-

moved therefrom, the inclination of the hangers being such that said hooks are disposed entirely outside of the frame when the carrier is in outer position whereby a magazine can be removed from or placed on the hooks without obstruction of other portion of the apparatus. 20 25

8. A rack as defined in claim 7 in which the hangers have portions extending below the hooks, said portions being adapted to cooperate with portions above the hooks to prevent the magazine from swinging on the latter. 30

In witness whereof we have subscribed our names.

FRED M. JOERNDT.
WILBUR A. JOERNDT.
